METHOD OF CRACKING OIL

Original Filed March 20, 1923 2 Sheets-Sheet 2

Fig. 2.

Fig. 3.

UNITED STATES PATENT OFFICE.

FRANK E. WELLMAN, OF KANSAS CITY, KANSAS.

METHOD OF CRACKING OIL.

Original application filed March 20, 1923, Serial No. 626,386. Divided and this application filed May 7, 1923. Serial No. 637,255.

The present application is a division of my copending application Serial No. 626,386, filed March 20, 1923.

My invention relates to cracking processes and especially to the cracking of hydrocarbons of high boiling point to produce hydrocarbons of low boiling point suitable for motor fuel.

- Among the objects of the invention are to
- 10 reduce the deposition of carbon on the still walls, to increase the amount of oil that can be treated in an apparatus of given content before it becomes necessary to shut down in order to clean out carbon deposits, and to
  - 15 effect an economical improvement in the ratio of yield and quality of product. Other objects will appear from a perusal of the following specification and drawings accompanying the same.
  - 20 In the drawings, which illustrate a preferred form of apparatus for carrying out my invention:

Fig. 1 is a vertical section through the center of the still taken on the line 1—1 of Fig. 2 with the tubes back of the plane of the section omitted for the sake of clearness;

Fig. 2 is a top plan view of the apparatus; and

30 Fig. 3 is a transverse or horizontal section taken on the line 3—3 of Fig. 1.

Referring to the drawings in detail, 1 designates a cylindrical furnace or heating chamber in which is mounted a circular series of vertical cracking tubes 2 arranged around the inside of the furnace wall and slightly spaced therefrom as shown in Figs. 1 and 3. The tubes are L-shaped with the bottom 3 of each tube projecting out through 35 and beyond the furnace wall where it is flanged and capped on the end as indicated at 4. The upper ends of the tubes 2 extend up through the furnace cover 5, and are capped as indicated at 6. Thus all the capped 40 ends of the tubes are outside of the furnace. To take vapor off from the oil while preventing the oil from foaming over into the vapor line, vaporizing drums 7 are provided around the top of the furnace, each of which 45 is connected with several of the cracking tubes 2 and a common vapor line 8, in the present embodiment, the sixteen cracking tubes being positioned among the four vaporizing drums in groups of four connected to 50 the drums through pipes 9, see Figs. 1 and 2.

Near the outer ends of the bottom portions 3 of the cracking tubes, connection is made outside the furnace between the cracking tubes and a manifold 10, extending around the furnace in the form of a split circle or C 60 with the ends 11 and 12 of the C-form closed or capped as indicated at 13 and 14. Outside circulating pipes 15 connect the vaporizing drums 7 below the liquid level, with manifold 10.

Near the outer ends of the bottom portions 3 of the cracking tubes, connection is made outside the furnace between the cracking tubes and a manifold 10, extending around the furnace in the form of a split circle or C 60 with the ends 11 and 12 of the C-form closed or capped as indicated at 13 and 14. Outside circulating pipes 15 connect the vaporizing drums 7 below the liquid level, with manifold 10.

A pair of pipes 16 and 17 connect with the ends 11 and 12, respectively, of the manifold 10, which pipes function alternately as supply and residuum draw-off pipes. To enable this interchange of function to be effected both pipes are extended from the still to the desired point of discharge through block valves 18 and 19, and between these valves and the still are both connected through switching block valves 20 and 21 to 75 the supply pipe 22. Thus with valves 21 and 18 closed, and 20 and 19 open, pipe 16 becomes the supply connection and pipe 17 the draw off, the rate of supply and draw off being controlled by valves 20 and 19, respectively. Obviously an interchange of function between pipes 16 and 17 will be effected upon a reversal of the setting of the valves 18, 19, 20 and 21.

To enable a return distillate such as the 80 reflux from a fractionator, to be fed into the still along with the supply, a conducting pipe 23 for such return distillate is connected to both pipes 16 and 17 through suitable switching valves 24 and 25 between the still and 90 the valves 20 and 21.

Heat is imparted to the cracking tubes within the furnace by a rotating source of heat, in the form of a rotating burner 26, similar to those of my co-pending applications Serial No. 523,062 filed December 17, 1921 and Serial No. 532,873, filed January 30, 1922. In the present arrangement the burner 26 is supplied with fuel and air through the fuel and air pipes 27 and 28 respectively, 95 which together with the rotary member 29 of a swiveled coupling 30 and diaphragm 31 are rotated within the circular series of cracking tubes by means of the bevel gears 32 and driving pulley 33 connected with a 100 suitable source of power, not shown. The bottom stationary part 34 of the swivel coupling is supplied with fuel and air through the stationary lead-in pipes 35 and 36, provided with valves 37 and 38, respectively. 110

For properly distributing the hot gases through the furnace and among the cracking tubes, I provide a set of baffles 39 supported by a rod 40 hung from the furnace cover 5 while for producing the required draft through the furnace a stack 41 is provided with which the upper portion of the furnace chamber connects through pipe 42.

In the operation of the still to carry out the preferred cracking process, the still is first charged, through one of the pair of pipes 16—17, for example pipe 16, by way of supply pipe 22, valve 20, pipe 16 and manifold 10, to the working level as indicated at 15 43, which charge may or may not be warmed or preheated. The burner 26 is then put in operation and the oil in the cracking tubes brought up to the desired cracking temperature. Vapors liberated from the oil in the vaporizing drums 7 are conducted off through the vapor line 8 to suitable fractionating, condensing and receiving devices, not shown, but which may be of any known or other suitable type, while enough make-up 20 is pumped in by way of the manifold 10 and pipe 16, to maintain the working level 43. After the make-up amounts to the original charge, residuum is drawn off and make-up or fresh oil is supplied at twice the rate of 25 evaporation so that the amount withdrawn in vapor form as well as the residuum drawn off is thereby compensated for, and a substantially constant amount of oil is maintained in the still. By governing these three 30 factors,—residuum draw-off, vapor draw-off, and make-up,—the percentage of yield is controlled. The vapor is continuously conducted off through the vapor line 8, while the level is maintained by drawing off the 35 residuum from the end 12 of the manifold 10 by way of pipe 17, the amount drawn off being controlled by valve 19. Intermediate distillates such as the reflux from a fractionator, are returned to the still along 40 with the oil supply by way of the return distillate pipe 23, valve 24, pipe 16 and manifold 10. When the run is half over the flow of supply and residuum draw-off is reversed by reversing the setting of the valves, that is 45 by closing valves 20, 24 and 19, and opening valves 21, 25 and 18.

The carbon deposit is thickest at the end where the residuum is drawn off and gradually down to nothing at the point where 50 charging is started. Thus by reversing the flow in the manner described, a fairly even deposition of carbon on the different tubes is brought about, resulting in a delay of the necessity for a shut-down for cleaning.

In one reduction to practice of the present invention, in which the outfit comprises eight three-inch tubes and eight four-inch tubes with ten feet in the furnace, I have run sixty 55 gallons an hour with very good results. In running this outfit, fifty barrels are put

through before shutting down for cleaning, with a yield of 40 per cent 60—61 degree gasoline based on the gas oil charged.

A larger still, under construction, designed to handle a run of 750 barrels of oil 70 before shut-down, is expected in practice to "crack" 1,000 barrels before shut-down, due to the relation between the contents and walls being entirely different.

Having thus described my invention, what 75 I claim and desire to secure by Letters Patent is:

1. The method of cracking oil which consists in heating the oil in a still, taking off the vapors and at the same time supplying 80 fresh oil to the still and drawing off residuum at different points, and reversing the said points of supply and residuum draw-off during the said heating and taking off of vapors.

2. The method of cracking oil which consists in charging a given amount of oil into a still at a given point, heating the oil and taking off the vapors while supplying additional fresh oil at sufficient rate to maintain 85 substantially the said given amount of oil in the still until said additional fresh oil amounts to substantially the original charge, then supplying fresh oil at twice the rate of evaporation and maintaining substantially 90 the said given amount of oil in the still by drawing off sufficient residuum at another point and reversing the said points of supply and residuum draw-off during the said heating and taking off of vapors.

3. The method of cracking oil which consists in charging a given amount of oil into a still or retort, heating the oil to the desired cracking temperature and taking off the 105 vapors, while supplying additional fresh oil at sufficient rate to maintain substantially the said given amount of oil in the still until said additional fresh oil amounts to substantially the original charge, then drawing off residuum and supplying fresh oil at a 110 rate sufficient to maintain substantially the said given amount of oil in the still until a given total amount of oil has been treated, the points of entrance of fresh supply into the still and of draw-off of residuum therefrom being interchanged after substantially 115 half the said given total amount of oil has been treated.

4. The method as claimed in claim 1 in addition to which a portion of the vapors taken 120 off is condensed and returned to the still with the supply of fresh oil.

5. The method as claimed in claim 2 in addition to which a portion of the vapors taken off is condensed and returned to the 125 still with the supply of fresh oil.

6. The method as claimed in claim 3 in addition to which a portion of the vapors taken off is condensed and returned to the still with the supply of fresh oil.

7. The method of cracking oil as claimed in claim 3 in addition to which the oil is caused to circulate by convection from a point below the liquid level near the point of vapor take-off through a relatively cool zone to the heated body of oil along with the said fresh oil supply.

8. The method of cracking oils which consists in causing the oil to circulate by convection upwardly through a heated zone, into a second relatively cool zone, and return downwardly through a third zone back into the heated zone, taking off the vapors at a point near the uppermost point in the cycle of circulation, and at two different points near the lowermost point in the cycle of circulation continuously drawing off residuum and supplying additional fresh oil at a rate sufficient to compensate for the amount withdrawn and to maintain a substantially constant amount of oil in the still, said draw off and supply being reversed and interchanged at intervals.

In testimony whereof I hereunto affix my signature.

FRANK E. WELLMAN.
